(57) CLAIM

The ornamental design for scissors, as shown and described.

DESCRIPTION

FIG. 1 is a top perspective view of scissors, showing my new design;

FIG. 2 is a bottom perspective view thereof;

FIG. 3 is a first side elevational view thereof;

FIG. 4 is a second side elevational view thereof,

FIG. 5 is a top elevational view thereof;

FIG. 6 is a bottom elevational view thereof,

FIG. 7 is a view similar to FIG. 1, the blades being in an opening position;

FIG. 8 is an end elevational view thereof, taken from the left of FIG. 3; and,

FIG. 9 is an end elevational view thereof, taken from the side opposite to that shown in FIG. 8.
